UNITED STATES PATENT OFFICE

CHARLES D. ROSSBACH, OF CHICAGO, ILLINOIS

WINDOW

Application filed April 18, 1931. Serial No. 531,097.

My invention relates in general to windows and more in particular to a ventilating type of window adapted to be set into a relatively larger window such as the usual type of large 5 stained glass windows commonly found in churches.

In general my present invention is an improvement on the window disclosed in Patent 10 #957,836, issued on May 10, 1910, to Benz and Rossbach.

The window shown in the patent referred to, in general has been found satisfactory and has been used extensively in church window and similar installations. It is subject to 15 some objection, however, due to the fact that at the points where the sash is hinged to the frame, there is a small area through which daylight can be seen, it being impossible or impractical in ordinary commercial practice 20 to fit the members sufficiently tightly so that no space can be seen at this point between the sash and frame. This prevents the window from being fully weather proof under all circumstances, and notwithstanding the fact 25 that this difficulty has been present in this type of window for years past, no satisfactory practical solution of the difficulty has been obtained.

The principal object of my present invention 30 is to improve windows of this type.

Another object is to make windows of this type entirely weather-proof at the places where the sash is hinged to the frame.

Another object is the provision of an improved pivot or hinge construction between 35 the sash and frame.

Other objects and features of the invention will be apparent from a consideration of the following detail description taken with the 40 accompanying drawings, wherein,

Fig. 1 is a front elevational view showing the improved ventilating window of my invention mounted in a larger window, the view being partly broken away to conserve space, 45

Fig. 2 is an enlarged vertical sectional view taken on the line 2-2 of Fig. 1, looking in the direction of the arrows.

Fig. 3 is a sectional view taken through the hinge or pivot portion on the line 3-3 of 50 Fig. 1,

Fig. 4 is a perspective view showing the sash removed from the frame,

Fig. 5 is a similar view showing the frame, and

Figs. 6 and 7 are fragmentary perspective 55 views of the sash and frame respectively, constructed as a modification of the principal design.

According to the main features of the invention, I provide hinge slots in the frame 60 with trunnions on the sash adapted to extend into the slots when the sash is inserted in the frame, the trunnions and lower edges of the slots forming pivots about which the sash hinges when the sash is opened. Cooperating hinge blocks or weather blocks provided on the frame and sash on opposite sides of the point of pivot entirely close the space normally to be expected between the sash and frame at the point of pivot. These weather 65 blocks secured to the frame and sash and disposed in a plane at right angles to the axis of the pivots also function as stops to prevent the sash from being opened too great a distance, although other stop means are shown 70 75 and may be used in actual practice.

Referring to Fig. 1 of the drawings, I show a relatively large window A, in which my improved ventilating window B is inset, this window B normally comprising only a relatively small part of the area of the window proper, but being sufficiently large to secure the necessary ventilation. This arrangement is customary in the art and does not represent a feature of my invention but is shown 80 for the purpose of illustrating a use to which the window may be put.

Refer now first to the frame shown in Fig. 5. This comprises top and bottom frame members 11 and 12 and side frame members 90 13 and 14. The top frame member has a small channel member 16 into which the glass or frame of the window above the inset window may be disposed and held by suitable means. It will be understood that similar 95 provision may be made entirely around the frame member, but in the present instance the frame member is shown as disposed on three of its sides within an outer wooden frame, constituting the frame of the main window. 100

Weather blocks 17 and 18 are secured to the inside of the frame by suitable means such as screws and pivot slots 19 and 21 are provided in the longitudinal or side frame members and extend partly into the weather blocks 17 and 18. These slots are of somewhat bayonet character, having a depression at their ends which is adapted to receive the pivot or trunnion members carried by the sash, which will be described. In this form the slot extending both through the frame member and a part of the weather block forms a relatively wide bearing surface for the trunnions. Looking at the weather block 17, the top portion 17a is relatively wide, but the bottom portion 17b is of less width, an angular portion 17c being shown between the wide and narrow portions. The block 18 is of course of the same shape.

Above the frame member on the outside thereof is a combination stop and weather strip 22, this strip extending from a place slightly above the pivot section on each side and extending entirely around the top frame member 11 (see Fig. 2). An inside combination stop and weather strip 23 is also provided, this stop extending on both sides from a point slightly below the pivot section and also extending across the bottom frame member 12.

The sash shown in Fig. 4 has a top member 24, a bottom member 26 and side members 27 and 28. The side members carry outwardly extending pivots or trunnions 29 and 31, the position being such as to cooperate with the slots 19 and 21 respectively in the frame member. Adjacent the trunnions are sash weather blocks 32 and 33 secured to the sash by suitable means such as screws. These sash blocks have approximately the same thickness as the corresponding and cooperating blocks on the frame and their width is such as to fit in the space on the frame not occupied by the blocks 17 and 18. The specific cooperation between these members will be explained more fully hereinafter.

The sash is also provided with a top inside weather strip 34, suitably secured to the inside of the sash, the projecting portion of this strip extending entirely around the top of the sash extending down on both sides to a position slightly above the trunnions. On the outside of the sash combination weather and stop strips are also provided. These include a bottom strip 36, which is substantially permanently secured in position and may form a permanent part of the sash, and removable side strips 37 and 38. These side strips cooperate with the strip 36 to form a continuous strip and they extend up to a point slightly below the trunnions 31.

It is of course understood that the sash carries any suitable type of glass which may be a clear glass, frosted glass, or it may be a colored glass such as used in churches. In this

work it is customary to employ double glass, and I show such an installation in which a parting strip 39 in the form of a channel separates the inside glass 40 and the outside or weather glass 40', which in most cases is a clear glass. It will be understood that this showing is illustrative, as the invention is not primarily concerned therewith.

Now as to the function of the weather blocks disposed on opposite sides of the point of pivot, it must first be observed that all of the combination stop and weather strips slightly overlap these blocks. The combination stop and weather strips cause the window to be tight and weather-proof at all places, except in the vicinity of the pivots. Since the weather blocks carried by the sash and frame are removably secured to the sash and frame respectively, the effect is the same as if the sash and frame overlap each other at these points, and accordingly the window as a whole can be made to be thoroughly weather-proof. It is understood, of course, that since the sash must be permitted to pivot freely, the several combination stop and weather strips provided cannot extend in any case far enough to interrupt the free pivoting movement of the sash. Accordingly, the weather blocks carried by the sash and frame are made to take up the space between the weather strips and overlap the strips to some considerable extent.

I shall now describe the cooperation between the members, referring to the weather block 33 and the weather block 17 for convenience of description, but it will be understood that the weather block 33 in fact cooperates with the block 18, which is not shown in its entirety in Fig. 5.

The block 33 has a vertical edge 33a facing the trunnion 31, and when the window is closed this lies relatively snugly against the vertical edge 17d of the block 17. When the sash is swung open this edge 33a rides around on the arcuate edge 17e until the bottom diagonal edge 33b engages against the slanting edge 17c on the block 17. It will be seen from this arrangement that these weather blocks are in sufficiently close engagement at all times as to make a substantially weather-proof joint. The narrow portion 17b permits a free movement of the block 17 as the sash is opened and also functions to carry the weather-proofing action of the block 17 well below the beginning of the contiguous weather strips.

The sash is designed to be relatively easily removed from the frame, and this is facilitated by the direction of inclination and the construction of the slots 19 and 21. In order to remove the sash, however, the strips 37 and 38 must first be removed. The sash is then swung open and pulled upwardly and inwardly so that the sash moves between the

strips 22 and 23 as it is being drawn out of the frame.

The sash and frame construction of the present invention can employ any of the usual types of latch mechanism and the like.

5 In Figs. 6 and 7 I show a conventional form of spring latch 41 operated by a rod 42 and bell crank 43, the bell crank being pivoted to the sash and having a chain 44 secured to one arm thereof. 10 A catch 46 carried by the frame is adapted to receive the chain and hold the window open a distance, determined by the place where the chain is secured in the catch.

In Figs. 6 and 7 I show a modified form, 15 which secures substantially the same results as the main frame previously described. In this form the sash member 138 carries a weather block 117 and a trunnion 131 forming part of the weather block. This trunnion can of course extend entirely through the member 138 to form a stronger construction. A slot 121 is formed in the frame member and a weather block 133 secured to the frame member is adapted to cooperate with the block 117. Substantially the same type of 25 construction and the same functions are performed by these two weather blocks, including the stop feature obtained by the use of the diagonal edges of the two blocks, which 30 are adapted to meet when the sash is swung open. It will be observed, however, that in this form less bearing surface is provided for the trunnion. The usual combination stop and weather strips shown in these two figures 35 also overlap the two inserted weather blocks disposed adjacent the point of pivot.

It is believed that from the foregoing description the manner of constructing and operating the invention will be clear. It is 40 understood that certain modifications and changes may be made without departing from the spirit and scope of the claims.

What I claim as new and desire to protect by Letters Patent of the United States is:—

45 1. In a window, a frame having top, bottom and side members and pivot slots in the side members, a sash having pivot members extending into said slots and cooperating therewith to form pivots for the sash, combination weather and stop strips on the frame and sash extending to points short of the pivots, whereby the sash can be swung open, and a weather block disposed between the sash and frame adjacent the pivot, and over-lapping 50 said weather strips, whereby a weather tight joint is provided at the pivot.

55 2. In a window, a frame having top, bottom and side members and pivot slots in the side members, a sash having pivot members extending into said slots and cooperating therewith to form pivots for the sash, combination weather and stop strips on the frame and sash 60 extending to points short of the pivots, whereby the sash can be swung open, a weather block secured to the sash between the sash and

frame adjacent the pivot, and a cooperating weather block secured to the frame and lying alongside the sash weather block when the window sash is closed.

3. In a window, a frame having top, bottom 70 and side members and pivot slots in the side members, a sash having pivot members extending into said slots and cooperating therewith to form pivots for the sash, combination weather and stop strips on the frame and sash extending to points short of the pivots, whereby the sash can be swung open, a weather block secured to the sash between the sash and frame adjacent the pivot, and a cooperating weather block secured to the frame and lying 75 alongside the sash weather block when the window sash is closed, and means on said first and second mentioned blocks for limiting the opening movement of the sash.

4. In a window, a frame having top, bottom 80 and side members and pivot slots in the side members, a sash having pivot members extending into said slots and cooperating therewith to form pivots for the sash, combination weather and stop strips on the frame and sash extending to points short of the pivots, whereby the sash can be swung open, and a weather block secured to the frame, having a slot coinciding with the slot in the frame, and a weather block secured to the sash and spaced 85 to have an edge lying immediately adjacent the contiguous edge of the first mentioned block.

5. In a window, a frame having top, bottom 90 and side members and pivot slots in the side members, a sash having pivot members extending into said slots and cooperating therewith to form pivots for the sash, combination weather and stop strips on the frame and sash extending to points short of the pivots, whereby the sash can be swung open, and a weather block secured to the frame, having a slot coinciding with the slot in the frame, a weather block secured to the sash and spaced to have 95 an edge lying immediately adjacent the contiguous edge of the first mentioned block, said block being shaped to remain in close association with each other when the sash is opened without binding.

6. In a window, a frame having top, bottom 100 and side members and pivot slots in the side members, a sash having pivot members extending into said slots and cooperating therewith to form pivots for the sash, combination weather and stop strips on the frame and sash 105 extending to points short of the pivots, whereby the sash can be swung open, and a weather block secured to the frame, having a slot coinciding with the slot in the frame, a weather block secured to the sash and spaced to have 110 an edge lying immediately adjacent the contiguous edge of the first mentioned block, said blocks being shaped to remain in close association with each other when the sash is opened without binding, and stop means on 115

the blocks for limiting the opening movement of the sash.

7. In a window, a frame having top, bottom and side members and pivot slots in the side members, a sash having pivot members extending into said slots and cooperating therewith to form pivots for the sash, combination weather and stop strips on the frame and sash extending to points short of the pivots, 10 whereby the sash can be swung open, weather blocks secured to the frame adjacent said slots, and cooperating weather blocks secured to the sash at the trunnions, said sash blocks extending beyond the trunnions and up to the 15 frame blocks.

8. In a ventilating window adapted to form an inset into a relatively large window, a frame adapted to be set in the plane of the large window, said frame having top 20 and bottom members, and side members, hinge blocks secured to the side frame members intermediate the ends thereof, and having oblique slots for receiving hinging trunnions, said blocks being of less width than the frame 25 members, a sash having top and bottom members, and side members, trunnions projecting from the outside of the side members and adapted to extend into said slots, and sash blocks disposed near the trunnions and cooperating with the hinge blocks to form a 30 weather-proof area between the sash and frame.

In witness whereof, I hereunto subscribe my name this 7 day of Mar., 1931.

CHARLES D. ROSSBACH.
